NONINTERFERING SUCCESSIVE SIGNALING SYSTEM

Manfred W. Muehler, Nutley, N. J., assignor to
American District Telegraph Company, Jersey
City, N. J., a corporation of New Jersey

Application December 21, 1934, Serial No. 758,582

16 Claims. (Cl. 177—361)

This invention relates to electric signal systems and transmitters and receivers therefor, and more particularly to systems wherein a large number of transmitters on the same circuit are prevented from interfering with each other, though it is noted that in some of the claims the invention is not limited to systems of the non-interfering type.

One object of the invention is to provide an improved system of this kind in which the transmitters are provided with motors operated from the central source of current at the receiving station, and wherein the motor is operated by current impulses and operates means for varying the strength of these impulses for sending code signals.

Other objects of the invention are to provide, in a system of this kind, improved signal means for indicating grounds and line breaks and their removal.

Additional objects of the invention are to improve generally the simplicity and efficiency of such systems and apparatus and to provide an apparatus of this kind which is reliable in operation, and economical to manufacture and install.

Still other objects of the invention will appear as the description proceeds; and while herein in details of the invention are described in the specification and some of the claims, the invention is not limited to these, since many and various changes may be made without departing from the scope of the invention as claimed in the broader claims.

The inventive features for the accomplishment of these and other objects are shown herein in connection with a positive non-interfering successive signaling system which briefly stated, includes a series of distant transmitters, each comprising a current motor, and a coding switch operated by the motor.

A starting line and an operating line are connected to a current source. A switch adapted to be operated by a sprinkler system valve or other device connects the motor in circuit with the starting line; and then means set in operation by the motor when started connect the motor in circuit with the operating line and disconnect the motor from the starting line and isolates the starting line to prevent other transmitters from being started.

In the accompanying drawings showing, by way of example, one of many possible embodiments of the invention,

Figs. 1 and 2 are complementary figures to

gether showing a diagram of the system, Fig. 2 showing that part of the system which is at the control or receiving station, Fig. 1, showing that part which is not at the control station.

Fig. 2a shows the matter of Fig. 2 in across-the-line diagram.

The line circuit consists of a three-wire loop comprising a common line A, a starting line B and an operating line C to which the individual transmitters 10 (Fig. 1) used for supervising various types of devices are connected. Two transmitters are shown, by way of example, connected to the line circuit, the wiring of one transmitter being indicated in detail but a larger number of transmitters would be used. All transmitters are alike except for a definite code tooth arrangement of the code wheel 11. The control center is shown in Fig. 2, to the right of the transmitter and is connected to the line circuit by suitable terminals.

Supervision

Lines A and B are supervised as follows: The current passes through a path from plus of the battery 12, 12' over conductor 13, over line A past the transmitters, over switch members 14, 15 of the switch S1, the coil of relay 16A, line wire B past the transmitters through conductor 17, #4 contact of relay X, to conductor 18 and minus of the battery. Relay 16A is thus normally kept energized supervising the line wires A and B as will be explained.

Line C is supervised by relay 20B as follows.

Current passes through a path which may be traced from plus through conductor 13, conductor 21, the #2 contact of relay X, conductor 22, winding U2 of relay U, conductor 23, the coil of relay 20B, switch elements 24, 25 of switch S2, from there through the third line wire C to terminal 4c and through conductor C4, the contact 5d of the master cam 28, conductor C3, in like manner through the various transmitters, which are all connected across terminals 4c and 3c, and then through line C, winding U1 of relay U, conductor 29, contact #6 of relay X, conductor 18, to minus. The two windings U1 and U2, of relay U have the same number of turns and are arranged to oppose one another so that the effect on relay U will be neutralized.

In case of a break in any of the line wires A, B or C, either relay 16A or relay 20B will become deenergized and close contact 16c or 20c and give a trouble signal by a lamp or bell or both as in standard practice, only the contacts of the relays being here shown.

5 The center of the battery is connected through conductor 30, contact #1 of relay X, conductor 31, to the coil of relay G, the other end of the coil G being grounded. A ground at any point of the external circuit of any of the three wires will operate relay G, which in turn gives the usual trouble alarm not shown.

Normal operation

- 10 When a device such as a gate valve, connected to the switch arm 33, changes its condition, it will close the circuit for operating a stepping magnet motor M of the associated transmitter. The motor M comprises a magnet 40M having separate 15 coils as will be explained. This circuit can be traced as follows: From terminal 2b, to which minus polarity is fed through #4 contact of relay X, conductor 17, and the line B, over conductor 34, switch elements 33, 35, conductor 36, of the 20 transmitter, transfer contact 2t of the transfer cam 31, conductor 38, contact 2d of the master cam, conductor 39 and to windings 40, 41 of the magnet 40M. The path from conductor 38 also branches through contact 4d of the master cam 25 through conductor 42 through the windings 43, 44 of the operating magnet. Thus the coil 40, 41 and the coil 43, 44 are in connected multiple through conductors 45, 46 and the line wire A to plus of the battery 12.
- 30 The transmitter magnet 40M will then attract its armature 48 and produce the following result: The ratchet pawl 48p will slip down over one tooth of the ratchet wheel 48 and engage the next lower tooth, and the armature will close contact 48A and establish a circuit from terminal line A (at which point plus polarity is available as traced above), through conductors 46, 49, contact 48A, contact 6d of the master cam switch, terminal 3c of the particular transmitter, the 35 third line wire C and through the various contacts 5d of the other transmitters over terminal 4c, 3c, through coil U1 of starting relay U, conductor 29, and the #6 contact of relay X to minus. Thereby the current flow through winding U1 of relay U is increased appreciably while the current flow through winding U2 of relay U is decreased somewhat by the shunt effect of this circuit. Winding U1 will therefore gain pre- 40 ponderance over winding U2 and operate the relay U which will start other relays as will be explained. When operated relay U closes its #1 contact and completes a circuit from plus through conductors 13, 50, #1 contact, conductor 51, the coil of relay P, its series resistance 52, conductors 53, 54, 55, 56 and 18 to minus thus operating relay P. Relay P then closes a circuit for relay Q which can be traced as follows. From plus through conductors 13, 50, 57, 58, the #3 contact of relay P, the conductor 59, the coil of relay Q 45 and its series resistance 60, conductors 53, 54, 55, 56 and 18 to minus. Relay Q operates and closes a holding circuit for itself through its #2 contact, conductors 58, 57, 50, 13, to plus; and by closing, its contact #1 connects conductor 51, 50 through conductor 62, contact #1 of relay Q, conductor 63 to the other terminal of the winding of relay P, thus shunting out the winding of P. When relay P thus drops out, a circuit is closed from plus through conductors 13, 50, the 55 #1 contact of relay U, conductor 51, the #1 contact of relay P, conductor 64, the #3 contact of relay Q, conductor 65 to the winding X1 of relay X, conductors 56, 18 to minus. Relay X is thus energized and first operates its armature 60 contact #1—2 breaking contact 2 and making

contact 1. By making contact 1 a locking circuit is closed for relay U from plus through conductors 13, 21, the #1 contact of relay X, conductor 67, the #2 contact of relay U, and through winding U3 of relay U, conductors 55, 56, 18 to minus. As will be seen this winding aids winding U1, and is also capable of holding relay U energized alone.

When #4 contact of relay X breaks, the minus feed is removed from the line B causing the 10 transmitter magnet M to release its armature and preventing other transmitters from starting by operation of switch member 33. The armature pawl 48p will then move the ratchet wheel 48w one step causing the master cam 28 to open 15 its contacts 2d, 4d, 5d, 6d and close contacts 1d, 3d, whereby the conductors 39, 42 and the two coils of the magnet motor M are disconnected from line B and connected through contacts 1d, 3d and conductors C4, C3 to terminals #4c and 20 #3c respectively, while the connection between the two terminals through contact 5d opens, preventing minus current from contact 3c from reaching transmitters to the right.

The instant when relay P released, the following events took place: The closing of contact #4 of relay P shuts out the coil of relay Q causing this relay to release. This removes the shunt from relay P allowing that relay to operate again. When relay P operates, a circuit is closed which 30 can be traced as from minus through conductor 18, the #5 contact of relay X, conductor 71, the #2 contact of relay P, conductor 72, winding X2 of relay X, the coil of relay C, the #3 contact of relay U, conductor 75, the line wire C, in series with contacts 5d of the intermediate transmitters over terminal 3c of the operated transmitter, contact 3d of its master switch and through conductor 42 and the right-hand coil to the transmitter magnet M and conductor 46 to 40 terminal 1a, where plus polarity is still available. The transmitter magnet is energized through this circuit, the pawl 48p, engaging the next ratchet tooth. It will be noted that the former shunt circuit through contact 48A is made ineffective by opening of contact 6d, and that only one transmitter is able to obtain this second impulse, as the transmitter located nearest to the lower ends of the lines A, B, C at the control center will open the line C by opening its contact 5d. 50 Therefore, if several transmitters should start up simultaneously, only one will be able to proceed farther than the first ratchet step. As the opening of #4 contact of relay X removes the minus feed from the line B, no other transmitter can 55 cut in on the one that is actually transmitting.

Relays P and Q continue to oscillate as described above in the following sequence; first relay P is energized; second, relay Q is energized; third, relay P is shunted and releases, and fourth, relay Q is shunted and releases. This cycle repeats itself for the full duration of the signal. Every time P closes its #2 contact, an impulse is sent out through conductor 72, coil X2, coil of relay C, #3 contact of relay U, conductor 75 and 60 the line C to the transmitter, as traced above, and every time P releases, this circuit is opened, causing the transmitter to release and move its ratchet wheel 48w and code wheel 11 one step for each impulse. The duration of the impulse is 65 primarily governed by the time of the release of relay P which can be made as slow as desired due to the shunt effect, and slightly by the time required for relay Q to operate while the duration of the space between impulses is primarily gov- 70 75

erned by the time of release of relay Q and slightly by the operating time of relay P.

As the code wheel 11 of the transmitter is rotated, its teeth will close its pen 11 upon contact 78 and 79 in accordance with the code cut on the wheel. The contact 79 has no effect at this time (contacts 3c, 4c being separated), but the closure of contact 78 forms a shunt 46, 11, 78, 80 which shunts out a portion 44 of the operating winding of the transmitter magnet increasing the current flow in the line circuit and also through relay C'. This relay C' is adjusted to operate under this increased current flow, but the current flow is not sufficient to operate relay C' when the shunt 46, 11, 78, 80 to the operating winding of the transmitter magnet is not applied. When relay C' closes its armature contact 81, it energizes a recording register 82 through conductors 83, 84, 56 and 18. This means that every time this happens, an impulse will be recorded on the tape in accordance with the code of the particular code wheel transmitting.

After a half, or some predetermined part, of a revolution, the master cam 28 brings its recess 85 to receive the pen 28d, the contacts are thereby restored to their original normal condition. In the meantime, the outer part 81' of the transfer cam 87, has engaged the pen t and opened the contact 2t, and closed contact 1t. The original starting circuit through conductor 36 to contact 2t is therefore now open. When relay P closes its #2 contact for the next impulse after this, the former operating circuit through conductor 18, contact #5 of relay X, contact #2 of relay P, conductor 12, the winding X2, the coil of relay C', the #3 contact of relay U and conductors 75 and line C is open at contacts 3d and 48A and the transmitter coil is no longer connected to terminal 3c; furthermore the #2 contact of relay X keeps open the return over the upper part of line C, switch 24, 25, the coil of relay 28B and winding U2 of relay U, conductor 22, contact #2 of relay X, conductor 21 to plus battery. The winding X2 is thus deprived of current. However, relay X was depending on this winding during the time an impulse is sent out to the line for holding up its armature as the circuit through its #1 winding was open due to relays P and Q being energized; and relay X will therefore release its armature restoring its contacts to the normal condition, opening its #1 contact and deenergize winding U3, and cause relay U to release. This relay opens its #1 contact and breaks the operating circuit of relay P. The pulsing relay P and associated relay Q therefore come to a stop in their normal deenergized position. The line circuit is restored to the original condition by contacts #2, #4, and #6 of relay X closing.

If another transmitter is waiting to send its signal, it will pull up its armature 48 as soon as #4 contact of relay X closes thereby starting the same cycle of events. Likewise, if the member 33 of the device switch of the transmitter just operated restores to the original condition a starting circuit is again closed for its transmitter this time over conductor 89 and through contact 1t of the transfer cam 87. This will cause the transmitter to start and cause a signal to be transmitted by the other half of the code wheel 11 which half is distinctive from the first one causing a distinctive signal indicating the restoration of the device switch member 33 to normal. If two transmitters are waiting at the same time only

the one nearest to the lower end of the line can advance to signal after contact 5d is broken.

Operation under trouble condition

In case of a break on line wires A or B, this break is indicated by the release of relay 16A. The double pole trouble switch S1 is then thrown to the upper position (manually, or automatically in any well known manner) thereby connecting both ends of line A to plus battery the upper end being connected through contacts 14, 90 and conductor 91. This change in switch S1 also connects both ends of line B together through contacts 92, 23 of switch S1. The system is now in operative condition as the transmitters located on one side of the break will receive their power over the upper end of lines A and B while transmitters located on the other side of the break will receive their power over the lower end of the lines A and B.

A break in line C will release relay 20B and deenergize coils U1, U2. Switch S2 is then thrown up connecting the upper end of line C through conductor 95 to coil V1 of relay V. If the break is located between the operating transmitter and the upper end of the line C, operation of the motor will energize coil U1 and the system will operate the same as before. However, if the break in line C is located between the operating transmitter and the lower end of the line C, the following circuit will be closed when contact 48A of the transmitter closes: from plus over line A, terminal 1a, conductors 46, 49, contacts 48A, 6d, 5d in series, terminal 4c, the line wire C, switch S2, conductor 95, winding V1 of a second starting relay V, conductor 97, the #3 contact of relay X to minus. Relay V operates and, closing of its #2 contact, starts the pulsing relay P through conductor 51 in the same manner as from the #1 contact of relay U as before described. Relay V locks in from plus through conductor 21, the #1 contact of relay X, #1 contact of relay V, coil V2 of relay V conductors 54, 55, 56 to minus. The rest of the operation will be the same as above except that the pulsing circuit for the transmitter is as follows: From minus through #5 contact of relay X, conductor 71, the #2 contact of relay P, conductor 72, winding X2, the coil of relay C', #4 contact of relay U, conductor 99, switch S2, line C, terminal 4c of the transmitter, contact 1d of the master switch, conductor 39, the left-hand coil 40, 41 of the transmitter, conductors 45, 46, terminal 1a and line A to plus. In this case contact 79 will transmit the code by shunting out a portion 41 of the left-hand coil of the transmitter through conductors 46, 46'.

Even if all three wires between two transmitters are open, any of the transmitters will still be able to send its signal after both switches S1 and S2 have been thrown over as will be evidenced from the above. If two or more transmitters located on opposite sides of the break are trying to send their signal at the same time, the one located nearest to the lower end of the lines will take preference, as it will operate the U relay as explained above which by opening its #4 contact and closing its #3 contact causes impulses to be sent out only through the lower part of the line C. A single ground on the line wires will not interfere with the operation but will be detected by the ground detector relay G. During the time of transmission, the relay G is disconnected from the system by the opening of contact #7 of relay X so that in case of a trouble ground that ground

will be the only one on the system and will, therefore, have no effect on its operation.

It must be understood that it is not essential to connect the two coils of the transmitter magnet in multiple for starting. It could also be arranged for series connection for starting. Likewise, the increase of current for coding purposes could be obtained by shunting a resistance instead of a portion of the winding or by shunting both.

10 The series connection of the motor coils, for starting the motor, is shown in Fig. 3. Starting current is introduced to the conductor 38 of Fig. 3 as described of Fig. 1, and finds a path through conductor 38, contact 2d, conductor 39', windings 40, 41, conductor 39'', contact 3d', conductor 42', windings 43, 44, conductors 45', 46, contact 1a and line A. The motor then closes contact 48A and steps the master cam 28 as described of Fig. 1. This opens contacts 2d, 4d', 5d and 6d, and 20 closes contacts 1d, 2d' and 3d', whereupon motor-operating current finds a path from the operating line C through conductor c4, contact 1d, conductor 39', windings 40, 41, conductor 39'', contact 2d' and conductors 45', 46, and another path 25 through conductor c3, contact 3d', conductor 42', windings 43, 44 and conductor 45'. This allows operation as previously described, the opening of contact 4d' breaking the series connection of the winding, the closing contact 2d causing conductors 45', 46'' to function as the conductor 45 in Fig. 1. The operation of contacts 11, 78 and 79 shunt out the windings 41 and 44 of Fig. 3 as in Fig. 1.

In the form of Fig. 4 the increase of coding current is formed by shunting the series resistances 41', 44', in series with the respective windings 41, 44, through conductors 46, 46', 80, by closing contacts 11, 78, 79 as in Fig. 1.

In the form of Fig. 5, the increase in coding current is accomplished by shunting windings 41 and resistance 41' through conductors 46, 46' and contacts 78, 79; and shunting winding 44 and resistance 44' through conductors 46, 80 and contacts 11, 78.

45 I claim as my invention:

1. In combination, a series of signal transmitters; an energized operating line and an energized starting line; each transmitter including a motor for operating the transmitter; means for connecting each motor in circuit with the starting line for energizing such motor; and means operated by each motor for connecting such motor to the operating line for operating the associated transmitter and isolating the starting line and the portion of the operating line on one side of the associated transmitter.

2. In combination, a series of signal transmitters; an energized starting line; each transmitter including a motor for operating the transmitter; means for establishing connection of such motor in circuit with the starting line for starting such motor; means set in operation by the motor on the establishment of such connection for rendering the starting line inoperative for starting the 65 motors of other transmitters; and means cooperating with such motor for continuing its operation and controlled by such motor for supplying driving current thereto for transmitting.

3. In combination, a series of transmitters; including a source of current; a common line connected to one pole of the source and passing near the transmitters in one direction; a starting line passing near the transmitters in the same direction and then to the second pole of the source; an 70 operating line passing near said transmitters to

the second pole; a starting relay comprising an operating magnet influenced by variations of current in the operating line; each transmitter comprising a stepping motor having an operating coil; switching means for connecting the coil between the common and starting lines for energizing the motor, means operated by the motor for connecting the common line to the operating line, thereby varying current in the operating line for operating the starting relay; means set in operation by the operation of the starting relay for disconnecting said second pole from the starting line, whereby the motor is deenergized, and then causing pulsation of the current in the operating line; means operated by the motor when thus deenergized, for connecting the motor coil between the common line and a point of the operating line and breaking the operating line beyond said point; code means operated by the motor on further impulses for causing intermittent variations in the current in the common line; and receiving means controlled by said variations.

4. In combination, an impulse circuit; means for supplying impulses to said circuit; a transmitter therein having a motor means for connecting the motor in the impulse circuit, whereby the motor is operated by impulses of said circuit; code means in the transmitter operated by the motor for causing intermittent variations in the strength of the impulses in the circuit; and receiving means controlled by said variations in said current.

5. In combination, a series of transmitters each comprising a motor and means for transmitting different successive signals; a starting line; an operating line; a transfer switch having two fixed elements and a movable element, and having its movable element connected to the starting line; connecting means for connecting the motor in circuit with one of the fixed elements of the transfer switch; means set in operation by the motor to connect said connecting means to the other fixed element of the transfer switch means operated by the motor when started to connect the motor in circuit with one end portion of the operating line and disconnecting the motor from the starting line; a source of current connected to said lines; and means set in operation by the motor when started for isolating the starting line from the source.

6. In combination a source of current; a line connected to one pole of said source; an operating line adapted to be connected at one or both ends to the other pole of the source; a transmitter comprising a motor comprising two coils either 55 of which can drive the motor; means connecting said coils in parallel between the first line and separated points on the operating line; and means for starting the motor and opening the line between said points.

7. In combination, a series of transmitters; a source of current; a common line connected to one pole of the source and a starting line passing the transmitters to the second pole of the source; an operating line passing from said first pole 65 near said transmitters to the second pole; a starting relay having and controlled by opposed coils in opposite ends of the operating line; a second starting relay; a trouble means operated when a break occurs in the operating line for disconnecting the operating line from the opposed coil nearest the first pole and connecting it through the coil of the second starting relay to the second pole; each transmitter comprising a motor having a pair of coils each able to operate 70 75

the motor; switch controlled means associated with each transmitter for connecting the motor coils thereof in parallel between the common and separated points of the starting line at such 5 transmitter for energizing the motor; means operated by the motor when started to connect the common line with the operating line and including means for operating the starting relay on the same side of the break with the operating 10 motor; means set in operation by the operated starting relay for disconnecting said second pole from the starting line; and means operated by the motor for connecting the motor between the common line and two points of the operating line 15 and breaking the operating line between said points.

8. In combination, a series of transmitters; a source of current; a common line connected to one pole of the source and passing near the transmitters; a starting line passing near the transmitters to the second pole of the source; an operating line passing near said transmitters to the second pole; a starting relay operated by current in the operating line; each transmitter comprising 20 a motor; switch controlled means for connecting the motor between the common and starting lines for energizing the motor; means operated by the motor when started to connect the common line with the operating line for 25 operating the starting relay; means set in operation by the operation of the starting relay for disconnecting said second pole from the starting line; means operated by the motor for connecting the motor between the common line and a 30 point of the operating line and breaking the operating line beyond said point.

9. In combination, a series of transmitters each comprising a motor; a control station including a source of voltage; a conductor connected to 40 one pole of the source and passing from said pole near the transmitters as a common line, and then back to the station and near the transmitters as a starting line, and then back to the second pole of the source; an operating line 45 passing from the first named pole through and past said transmitters in the same direction to the second pole; a starting relay comprising an operating magnet having opposed coils interposed in opposite ends of the operating line; means for connecting the motor in circuit with 50 the starting line; means set in operation by the motor when started to connect the motor in circuit with the operating line, operating the starting relay, and disconnecting the motor from the starting line; and means set in operation by 55 the starting relay for disconnecting said second pole from the starting line.

10. In combination, a series of signal transmitters; an operating line and a starting line 60 passing the transmitters; a motor for each transmitter adapted to be started by current from the starting line; and means set in operation by the motor in circuit with the operating line thereby causing current change therein, means set in 65 operation by the current change in the starting line for causing the operating line to operate the started motor, and for preventing the starting line from initiating the operation of other transmitters.

11. In combination, a series of signal transmitters; an operating line and a starting line; a motor for each transmitter; means for connecting any one of said motors in circuit with the starting line for energizing such motor; switch- 5 ing means operated by the motor for connecting the switching means in circuit with the operating line, thereby causing current change in the operating 10 line; and means set in operation by such change for supplying current to the operating line to operate such connected motor, and for preventing the starting line from initiating the operation of any of the other transmitters, thereby to prevent confusion of signals. 15

12. A system as in claim 11 comprising a coding means operated by the motor for varying the current in the operating line.

13. In combination, a series of signal transmitters; an operating line and an energized starting line passing all of the transmitters; a 20 motor for each transmitter; means for connecting any one of said motors in circuit with the starting line for energizing such connected motor; and means set in operation by such connected motor for connecting such motor to the 25 operating line, to operate such motor and its associated transmitter, disconnecting the portion of the operating line on one side of such operating transmitter, and deenergizing the starting line at all of the transmitters. 30

14. In combination, a series of signal transmitters; an energized operating line and an energized starting line passing the transmitters; an energized common line of different potential from the other lines; a motor for each transmitter; 35 means for connecting any of said motors between the common line and starting line for starting such motor; and means operated by such started motor for connecting such motor between the common and operating lines and rendering 40 the starting line incapable of starting any of the other of said motors.

15. In combination, a series of signal transmitters; an energized operating line and an energized starting line passing the transmitters; an 45 energized common line of different potential from the other lines; a motor for each transmitter; switch means for each motor for connecting such motor between the common line and starting line for starting such motor; means operated by such 50 motor for connecting such motor between the common and operating lines and deenergizing the starting line for rendering it incapable of starting any of the other of said motors; and code transmitting means operated by each motor for 55 establishing a connection of variable conductivity between the operating and common lines.

16. In combination, a series of signal transmitters, each comprising a motor for operating such transmitter; a starting line; means associated with each motor for connecting such motor in circuit with the starting line to start such motor; a disabling means common to and remote from the transmitters and adapted when operated for disabling the starting line for starting the motors; and an electrical means operated by each motor when started for operating the disabling means. 60 65

MANFRED W. MUEHTER.
